US00D741488S

(12) **United States Design Patent**
Tohmeh et al.

(10) **Patent No.:** **US D741,488 S**
(45) **Date of Patent:** **** Oct. 20, 2015**

(54) **SPINAL FUSION IMPLANT**

(71) Applicant: **NuVasive, Inc.**, San Diego, CA (US)

(72) Inventors: **Antoine G. Tohmeh**, Spokane, WA (US); **Joseph Clark**, San Diego, CA (US)

(73) Assignee: **NuVasive, Inc.**, San Diego, CA (US)

(**) Term: **14 Years**

(21) Appl. No.: **29/486,401**

(22) Filed: **Mar. 28, 2014**

Related U.S. Application Data

(63) Continuation of application No. 14/149,550, filed on Jan. 7, 2014, now abandoned, which is a continuation of application No. 12/329,195, filed on Dec. 5, 2008, now Pat. No. 8,623,088, which is a continuation-in-part of application No. 11/488,744, filed on Jul. 17, 2006, now Pat. No. 7,867,277.

(57) **CLAIM**

The ornamental design for a spinal fusion implant, substantially as shown and described.

DESCRIPTION

FIG. 1 is a perspective view of a spinal fusion implant showing our new design;

FIG. 2 is a side view of the spinal fusion implant of FIG. 1; and,

FIG. 3 is a plan view of a proximal end view of the spinal fusion implant of FIG. 1.

The broken lines illustrate portions of the spinal fusion implant and form no part of the claimed embodiment.
